UNITED STATES PATENT OFFICE.

CHARLES F. LANCASTER AND JAMES D. ANDREWS, OF PETOSKEY,
MICHIGAN.

VENT FOR CHURNS.

SPECIFICATION forming part of Letters Patent No. 760,693, dated May 24, 1904.

Application filed June 29, 1903. Serial No. 163,651. (No model.)

To all whom it may concern:

Be it known that we, CHARLES F. LANCASTER and JAMES D. ANDREWS, citizens of the United States, residing at Petoskey, in the county of Emmet and State of Michigan, have invented 5 certain new and useful Improvements in Vents for Churns, of which the following is a specification.

This invention provides a peculiar form of 10 vent for revolving churning, having for its essential object to so dispose the vent as to prevent the formation of gas within the churn due to the constant agitation of the fluid which is received therein. It is well known that in 15 this construction of churn the revolution of the body after the cream is placed therein causes the formation of no small amount of gas, which when the churn is opened preparatory to removing the contents after operation 20 of the same forces out the liquid contents of the receptacle under great pressure, and this is the cause of great inconvenience at times, as will be readily apparent to those cognizant with this art.

25 For a full description of the invention and the merits thereof and also to acquire a knowledge of the details of construction of the means for effecting the result reference is to be had to the following description and drawings 30 hereto attached.

While the essential and characteristic features of the invention are susceptible of modification, still the preferred embodiment of the invention is illustrated in the accompanying 35 drawings, in which—

Figure 1 is an elevation of a revolving churn, having the body thereof broken away and shown in section to illustrate the peculiar form of vent which constitutes the invention. Fig. 40 2 is a detail sectional view, the churn broken away, showing more particularly the peculiar construction of the vent. Fig. 3 is a detail perspective view of the vent-tube and the securing-collar coöperating therewith.

45 Corresponding and like parts are referred to in the following description and indicated in all the views of the drawings by the same reference characters.

The invention is adapted for application to

any ordinary structure of revolving churn, 50 that illustrated in the drawings consisting of the churn-body 1, mounted for revolution upon suitable supports 2, which are projected from a base 3. The churn is operated by a crank 4, disposed upon one of the journals 5 and provided with a crank-handle 6. It will be understood that any suitable construction 55 may be utilized within the contemplation of our invention as regards the structure of the parts hereinbefore described. 60

The vital feature of the invention, as before premised, lies in the peculiar form of vent utilized. The vent consists of a tube 7, which is disposed upon the hollow journal 8 of the churn-body 1, extending through the said 65 journal in a manner readily seen. The tube 7 is provided with the inner curved end portion 7^a, the special advantage of which is to prevent escape of the contents of the churn-body through the vent-tube, at the same time 70 permitting, however, escape of any gas which may be formed during the agitation of the contents of the receptacle. Adjacent the curved end portion 7^a of the vent-tube 7 and upon the inside of the churn-body 1 is disposed a stop-collar 9, which is located adjacent the inner end portion of the hollow journal 8. A washer or analogous device may be substituted for the element 9 as far as utility of the same is 75 concerned, since the latter would answer the 80 purpose as well as the collar illustrated. In order to hold the vent-tube in position and to maintain the curved end portion 7^a thereof in its relative position with the open end of the tube downward, a set-collar 10 is removably 85 disposed upon the outer end portion of the tube. The set-collar 10 may be held in the position shown by any suitable means, such as a set-screw or the like. In the drawings a weight 11 depends from the vent-tube, which weight 90 normally holds the curved end portion 7^a thereof in its proper position, and this weight 11 is connected to the set-collar 10 by means of a rod 12, which rod may be permanently 95 formed with the weight. The rod is threaded upon its upper end, and this threaded end portion of the same is adapted to be screwed into an opening in the set-collar 10 and into

contact with the vent-tube 7 to secure the set-collar 10 to the vent-tube, as well as to support the weight upon the set-collar. It will thus be seen that during the revolution of the 5 churn-body 1, which is actuated by the crank-handle or other equivalent device, the vent-tube is normally held in position with the curved end portion thereof in an uppermost position. During the revolution of the churn 10 the gas which is formed by the agitation of the contents of the receptacle is allowed to escape through the vent-tube, thus preventing the resulting inconvenience described above.

The device embodies a high degree of simplicity, and consequent cheapness relative to the cost of construction, this being quite an essential advantage thereof. The device is also susceptible of a broad application in that it may be disposed upon churn-bodies with 15 20 but a slight modification, if any, relative to the construction thereof.

Having thus described the invention, what is claimed as new is—

In a churn, the combination with a body, a 25 hollow journal disposed upon the said body and having a portion passed through an opening in the body, an annular flange disposed

upon the journal and adapted to abut against the outer side of the body adjacent the opening aforesaid, securing means passed through the flange to secure the journal to the body, a vent-tube passing through the said hollow journal having its inner end curved within the churn-body and its outer end projected beyond the journal, a stop-collar disposed upon the inner portion of the vent-tube to limit the outward movement thereof, a set-collar mounted upon the outer end of the vent-tube to limit the inward movement thereof and provided with a threaded opening, a rod 30 35 40 having a threaded end to be screwed in the threaded opening of the set-collar to secure the same to the vent-tube, and a weight disposed upon the rod and adapted to hold the curved inner end of the vent-tube at an ascertained position.

In testimony whereof we affix our signatures in presence of two witnesses.
